(57) **CLAIM**

The ornamental design for a spraying system for a cleaning wiper or cleaning mop, as shown and described.

DESCRIPTION

FIG. 1 is a top right perspective view of the spraying system for cleaning wiper or cleaning mop in accordance with my invention, the broken lines not forming a part of the claimed design and merely showing environment;

FIG. 2 is a bottom right perspective view thereof;

FIG. 3 is a front view thereof;

FIG. 4 is a right side elevational view thereof;

FIG. 5 is a left side elevational view thereof;

FIG. 6 is a back view thereof;

FIG. 7 is a top view thereof; and,

FIG. 8 is a bottom view thereof.
